MULTIPLE V ANTENNA SUSPENSION

Haraden Pratt, Douglaston, N. Y., assignor to
 Mackay Radio & Telegraph Company, New
 York, N. Y., a corporation of Delaware

Application May 4, 1937, Serial No. 140,582

7 Claims. (Cl. 250—11)

The present invention relates to antenna arrays of the multiple V type, and particularly to suspension arrangements for quadruple V antenna arrays.

5 It is an object of the present invention to provide a suspension arrangement for a quadruple V antenna array which shall support the necessary conductors of such a quadruple V array by means of the minimum amount of supporting equipment. In particular it is an object of the present invention to reduce the number of poles required for supporting a multiple V antenna array and further it is an object to require a minimum total length of inactive tension

10 strands.

15 A feature of the present invention is the support of a quadruple V array by means of only six poles or towers. Another feature is the support of such an array according to a simple arrangement which may be readily laid out for various lengths and angles of antennae and which requires only a short total length of inactive tension strands. The antenna array supporting arrangement of the present invention has the further feature that the tension in the inactive supporting tension strands are maintained within reasonable limits and are for the most part not higher than the tension in the radiating conductors of the array itself, so that most of the

20 lengths of connecting tension strands may be constructed of the same material as the conducting wires of the antenna array itself, and so that insulators, coupling members, and poles of unusual strength will not be required.

25 The arrangement of the present invention is especially intended for use with quadruple V antenna arrays in which the angle between the axis of the array and any of the arms of the component V's is between five and thirty-five degrees, and particularly for arrays in which this angle is between fourteen and twenty-five degrees. In the description of the present invention it will be assumed that the various arms of the quadruple V are of equal length or of substantially equal length, since such an arrangement is usual in such multiple V arrangements.

30 The present invention may best be understood by reference to the drawing which schematically represents a plan view of the essential conductors of the quadruple V array and the supporting arrangement for supporting such conductors in accordance with the present invention.

35 The points P, R, S, T, represent the vertices of the four individual V shaped antennae which comprise the array. The points A, B, C and D,

represent the ends of the arms of the corresponding V's on one side while the points A', B', C' and D', represent the corresponding ends of the arms on the other side. Assume that each of the four V's of the array subtends the same central angle which is represented as $2W$, the angle W representing the inclination of any one of the arms of the V's with respect to the principal axis of the array. Since all four conductors on one side of the array are parallel to one another the direction of any of the conductors may be called the "conductor direction" of that side of the V array. This conductor direction as well as the direction of the principal axis of the whole array will be used as reference direction for specifying the angular orientation of the various supporting strands later to be described.

40 According to the present invention the complete quadruple V array is supported from only six poles represented by the small circles 1, 2, 3, 20 4, 5 and 6 adjacent points P, S, F, D, F' and D'. The vertex of the outermost V antenna 11—21 is supported directly from pole 1, similarly the second innermost antenna 13—23 has its vertex supported directly from the pole 2. The vertices, 25 R and T, of the other two antennae 12—22 and 14—24 are supported from poles 1 and 2, respectively, by means of the transmission lines P—R and S—T which also serve to carry the power to or from the antennae 12—22 and 14—24. Although each of these transmission lines P—R and S—T is represented by a single line it will be understood that they will ordinarily be two-wire transmission lines and will preferably be 30 constructed of the same type of conductor as the radiating arms of the antennae themselves. In the preferred construction, in fact, these transmission lines are merely extensions of the antenna arms, and the two wires are held closely adjacent to each other by insulators at the points 35 R and T and at suitable intervals between these points and the poles 1 and 2. These transmission lines may be directly connected to antennae 11—21 and 13—23 at the points P and S, or may be dropped down the poles alongside of similar 40 transmission lines from the antennae 11—21 and 13—23 so that the four transmission lines may be suitably interconnected below. Although as described, the transmission lines are preferably 45 employed for supporting vertex R from point P, and vertex T from point S, it is within the scope of my invention to employ simple tension strands for the links P—R and S—T in which case the transmission lines may be dropped down directly 50 55

from the vertices of the various antennae, or may be led down in any suitable manner.

The outer ends that is, the ends remote from the vertices of the V's of arms 11, 12, 13 and 14, are supported as follows: The outer end of the conductor 14 is supported directly from pole 4. The outer end of conductor 11 is supported by tension strand 15 from pole 3. The outer end of conductors 12 and 13 are supported from junction 10 points E and C of tension arcs 17, 18 and 19, as shown, the end of conductor 13 being directly attached to this tension arc at the point C, while the end of conductor 12 is supported from the point E of the tension arc by means of tension strand 16. The tension arc 17, 18, 19 is supported at points F and D from poles 3 and 4.

It is apparent that tension strands 15 and 16 are in line with the conductors 11 and 12, or in other words these tension strands have a zero angle with respect to the conductor direction of the corresponding side of the V array. The angles which strands 17, 18 and 19 make with this conductor direction are denoted by X, Y and Z, respectively. Similarly it is apparent that 25 the tensions *fa* and *eb* in strands 15 and 16 are equal to the tensions employed in the conductors 11 and 12. Upon the assumption that the tensions in conductors 11, 12, 13 and 14 are all 30 equal and are represented by K, the tensions in strands 15 and 16 will then be simply K. The tensions in strands 17, 18 and 19 of the tension arm will be denoted, respectively, by *cd*, *ce* and *ef*, respectively.

According to one feature of the present invention tensions *af*, *eb*, *cd*, *ce* and *ef* are for the most part arranged to be not greater than K. According to the preferred arrangement all but one of these tensions are maintained equal to or less than K, the only tension which exceeds this 35 value being tension *cd* in tension strand 17. At the same time, however, the sum of the lengths of tension strands 15, 16, 17, 18 and 19 is kept at a minimum so as to minimize distortions of the radiation pattern or reception pattern, reduce 40 parasitic losses and decrease the cost of the equipment, especially the cost of the insulators necessary for breaking up the tension strands into small non-oscillating lengths. In order to minimize the total footage of tension strands 45 the location of poles 3 and 4 and the orientation of strands 17, 18 and 19 are so selected that angle X will be comparatively small.

In accordance with an important feature of my invention poles 3 and 4 are so located and strands 50 17, 18 and 19 are so oriented that angle X will be substantially equal to angle W. At the same time angle Z is arranged to be as large as it can practically be made without necessitating excessive tension in the tension strands 18 and 17, this 55 angle Z being in any case greater than twice angle X. In order to avoid too great tension in strands 17 and 18, the angle Z should not exceed the supplement of 3X and should preferably be somewhat lower.

60 In the preferred arrangement angle Z equals 90° minus X, the angle Y equals 2X and the tensions in strands 19, 18 and 17 are, respectively, .7 K, K and 1.9 K approximately. Such a value of Z enables the same type of wire to be used for 65 tension strands 18 and 19 as for tension strands 15 and 16 when these strands 15 and 16 are just safely strong enough to support the tension K. With this arrangement it is preferred to make all 70 the tension strands excepting 17 of the same type 75 of wire as the conductors 11, 12, 13 and 14. The

tension strands may then be sub-divided by the insertion of insulators at suitable intervals so as to prevent the absorption of power and the distortion of the radiation or reception pattern of the array. 5

Although the preferred value for angle Z is in the neighborhood of 90° minus X as above explained, very satisfactory results may be obtained when this angle is considerably smaller. A convenient smaller value of Z is obtained by 10 making Z and Y equal, in which case each of these angles will have a tangent which is three times as great as the tangent of X. In this case the tension in strands 18 and 19 will be about three-fourths of K and the tension in strand 17 15 will only be 1.6 K.

It will be noted that when X is equal to W as above described, strand 19 is exactly perpendicular to the principal axis of the array and strand 17 is parallel to this axis. This parallelism of 20 strand 17 with respect to the axis is preferably maintained whatever value is chosen for angle Z since this parallelism reduces the length of inactive tension strands required, by eliminating tension strands between conductor 14 and pole 4, as 25 well as eliminating the need of an extra tension strand between conductor 13 and point C of the tension arc.

Not only does this reduce the total length of 30 inactive tension strands employed, but also this parallelism of strand 17 simplifies the fittings and reduces the number of insulators required, as well as providing a very suitable and convenient layout.

The following numerical illustration of an antenna 35 constructed in accordance with my invention may be useful as a concrete illustration of how the above described rules are applied. The angle W is 20°, the total angle between the two conductor directions of the two arms of the V 40 array being 40°. The distance from P to R is 85 feet, from R to S 75 feet, and from S to T 85 feet. The conductors 11, 12, 13, 14 are each somewhat more than 400 feet long, the conductors 21, 22, 23 and 24 being of this same length. 45 Angle X is 20°, angle Y and angle Z are each 47.5°. Each of the conductors 11, 12, 13 and 14 is drawn up to a tension of 1000 pounds, the tension in strands 16 and 15 being, of course, 1000 pounds also. The tensions in strands 18 and 19 are each 50 equal to approximately 720 pounds; and the tension in strand 17 is approximately 1600 pounds. The conductors 11, 12, 13 and 14 are constructed of number 6 copper coated steel wire; and this 55 same type of wire is employed for tension strands 15, 16, 18 and 19. Tension strand 17 which must withstand a somewhat higher tension is made of quarter-inch stranded wire rope. All these 60 inactive tension strands 15, 16, 17, 18 and 19 are broken up into short lengths by the insertion of strain insulators at suitable intervals, so as to prevent these strands from picking up appreciable quantities of energy and thus modifying the radiating or receiving pattern.

While I have described the particular embodiments of my invention for the purposes of illustration, it should be understood that various modifications and adaptations thereof occurring to one skilled in the art, may be made without 65 in the spirit of the invention, as set forth in 70 the appended claims.

What is claimed is:

1. A supporting structure for an array of at least four V antennae comprising a first pair of poles disposed along the axis of the array, two 75

other pairs of poles disposed symmetrically about said axis, each of said other pairs being in the vicinity of the arm ends of one side of said array, a tension arc extending between the two poles of each such other pair, means for supporting the vertices of the four V antennae from said first pair of poles and means for supporting the arm ends of said four antennae from said other pairs of poles and the tension arc extending between them.

2. A supporting structure for an array of at least four V antennae comprising a first pair of poles disposed along the axis of the array, two other pairs of poles disposed symmetrically about said axis, each of said other pairs being in the vicinity of the arm ends of one side of said array, the direction of alignment of the two poles of each such other pair forming an acute angle with the axis of the array, a tension arc extending between the two poles of each such other pair, means for supporting the vertices of the four V antennae from said first pair of poles and means for supporting the arm ends of said four antennae from said other pairs of poles and the tension arc extending between them.

3. A supporting structure for an array of at least four nested V antennae comprising a first pair of poles disposed along the axis of the array, means for supporting the vertices of the four antennae from said pair of poles, two other pairs of poles disposed symmetrically about said axis, each of said other pairs being in the vicinity of the arm ends of one side of said array, a tension arc extending between the two poles of each such other pair, and means attached at intermediate points of each of said tension arcs for supporting the outer ends of a plurality of the V antennae.

4. A supporting structure for an array of at least four nested V antennae, one being innermost, one outermost, and the other two intermediate the innermost and outermost, comprising a first pair of poles disposed along the axis of the array, two other pairs of poles disposed symmetrically about said axis, each of said other pairs being in the vicinity of the arm ends of one side of said V array with one pole of each pair closer the axis of the array than the other, a tension arc extending between the two poles of each such other pair, means for supporting the outer ends of the innermost and outermost V antennae from said other pairs of poles and means attached at two intermediate points of each of said tension arcs for supporting the outer ends of the two intermediate V antennae, that section of each tension arc which lies between that pole of the associated pair which is closer to the axis of the array and that one of the intermediate points of the tension arc which is nearest to said last mentioned pole being substantially parallel to the axis of the array.

5. A multiple array comprising at least four nested parallel V antennae, one being innermost, one outermost, and the other two intermediate the innermost and outermost, supporting means for the vertices of said antennae, supporting means on one side of the array comprising a pair of poles of which one is in line with the arm of

the innermost V and the other is in line with the arm of the outermost V, supporting connections from each of said poles to the arm with which it is aligned, a tension arc extending between said pair of poles, supporting means from each intermediate antenna arm to an intermediate point on the tension arc which is in line with said arms and on the other side of the axis of the array, a similar supporting arrangement for the ends of the antennae arms on said other side comprising a pair of poles, a tension arc and supporting means.

6. A multiple array comprising at least four nested parallel V antennae, one being innermost, one outermost, and the other two intermediate the innermost and outermost, supporting means for the vertices of said antennae, supporting means on one side of the array comprising a pair of poles of which one is in line with the arm of the innermost V and the other is in line with the arm of the outermost V, supporting connections from each of said poles to the arm with which it is aligned, a tension arc extending between said pair of poles, supporting means from each intermediate antenna arm to an intermediate point on the tension arc which is in line with said arms, the angular direction of the successive segments of the tension arc being such that the tension in each of two segments of the tension arc is substantially equal to the tension in the antenna wires themselves, and on the other side of the axis of the array a similar supporting arrangement for the ends of the antennae arms on said other side comprising a pair of poles, a tension arc and supporting means.

7. A quadruple V array comprising a first, a second, a third and a fourth V of antenna wire parallelly disposed within one another in the order mentioned, a first and a second pole located adjacent the vertices of said first and third V's respectively, supporting connections from said first pole to the vertices of said first and second V's, supporting connections from said second pole to the vertices of said third and fourth V's, a third pole located in line with but remote from one arm of said first V, a fourth pole located adjacent the end of the corresponding arm of said fourth V, a supporting connection from said third pole to the end of the corresponding arm of said first V, a connection from said fourth pole to the end of the corresponding arm of said fourth V, a tension arc connected between said third and fourth poles, a connection from an intermediate point of said arc to the outer end of the corresponding arm of said third V, a connection from another intermediate point of said tension arc to the outer end of the corresponding arm of said second V, said last named connection comprising a tension strand, and another supporting arrangement for the other arms of said first, second, third and fourth V's comprising two poles, a tension arc, and connecting means similar to the arrangement for supporting said first mentioned arms of said first, second, third and fourth V's.

HARADEN PRATT. 65
